UNITED STATES PATENT OFFICE.

EDWARD E. LA SCHUM, OF NEW YORK, N. Y.

COMBINATION NOVELTY.

Application filed October 15, 1926. Serial No. 141,861.

My invention relates to a novel form of bottle opener, for corked and wired or metal capped bottles, which may be assembled for pocket carrying in a manner which eliminates the protrusion of any sharp points or bulky portions which would catch in the clothing or cause the pocket thereof to bulge in an objectionable manner. The device, when assembled for use, provides an instrument for snapping or breaking a sealing wire on a bottle, an instrument for pulling the cork from a bottle, and an instrument for removing a crimped metal cap from a bottle.

The wire snapper is in the form of a screw-driver which may be used independently as such, and is further employed as a handle for a cork puller. When snapping a sealing wire, the cork puller functions as a handle for the wire snapper; and when removing the metal cap from a bottle the cork puller functions as a lever, and the point of the wire snapper functions as a pivot element therefor, the actual cap removal being accomplished by a shoulder formed on the head of the cork puller.

Several methods of employing the novelty are illustrated in the accompanying drawing, of which:

Fig. 1 illustrates the novelty as assembled for pocket carrying;

Fig. 2 illustrates the novelty as assembled for use as a corkscrew;

Fig. 3 illustrates the novelty as being employed for removal of a metal cap;

Fig. 4 illustrates the employment of the novelty as a tool for breaking the sealing wire on a bottle; and

Fig. 5 illustrates the screw-driver as removed from the corkscrew for independent employment.

My combination novelty bottle opener comprises, in its present form, a cork puller 1 and a wire snapper in the form of a screw-driver 2. The cork puller comprises a helicoid spindle or screw 3 pointed at one end and flared outward at its opposite end to form a cylindrical head 4. The head 4 is provided with an annular groove 5, for purposes hereinafter described, and a cylindrical opening 6 of even diameter throughout, the said opening 6 extending completely through the head 4, and substantially at right angles to the axis of the screw 3.

It will be noted that the screw 3 is left-handed for the purpose of perpetrating a

humorous situation at the expense of a person using the device, who is unfamiliar with this idiosyncrasy of the device, the natural inclination of the user of a corkscrew being to turn the corkscrew clockwise in order to cause the screw to penetrate the cork, whereas it requires a turning in an anti-clockwise direction of my novel corkscrew to effect the penetration of the cork.

The wire snapper or screw-driver 2 comprises a spindle or shank 7 and a nurled head 8. The shank 7 is flattened or wedge-shaped at the end opposite the head 8 in the usual manner, but intermediate the point of the screw-driver and the head thereof the shank 7 is slightly tapered toward the point. When the screw-driver 2 is employed as a handle for the corkscrew the shank 7 is inserted in the opening 6 of the head 4 of the cork puller, as shown in Fig. 2. The taper of the shank 7 is such as to permit only a partial longitudinal movement through the opening 6, the wall of which binds against the shank and maintains the screw-driver in a position extending a substantially equal distance from either side of the head 4, as shown in Figs. 2, 3, and 4.

The annular groove 5, in the head 4 of the cork puller, functions when the device is employed for removing metal caps from bottles as shown in Fig. 3, the lower wall of the groove providing a shoulder 9 which is adapted to engage the lower crimped edge 10 of the bottle cap at one side of the bottle, and the point 11 of the screw-driver engages the top 12 of the cap at the side opposite that engaged by the shoulder 9.

The process of breaking the sealing wire of a bottle will be obvious upon reference to Fig. 4, which illustrates the point 11 of the wire snapper or screw-driver as having been forced under the wire 13, the cork puller 1 acting in the capacity of a handle or lever to snap or pry the wire loose from the cork.

The screw-driver 2 and the inner diameter of the helicoid spindle 3 of the cork puller are of such relative proportions that the shank 7 of the screw-driver may be coaxially aligned with and positioned within the centrally formed channel of the helicoid spindle 3 for carrying, as shown in Fig. 1, the taper of the shank 7 functioning to cause the said spindle to be engaged by the first turn of the screw, and thereby frictionally

retain the spindle 7 within the helicoid spindle 3. The point 14 of the helicoid spindle 3 adheres closely to the tapered shank 7 intermediate the head 4 of the cork puller and the head 8 of the screw-driver, thereby preventing the point 14 from catching in the clothing of a person carrying the device.

In manufacture, the cork puller and the screw-driver may be turned from a round rod of a diameter substantially equal to the diameter of the heads of these elements, on automatic machines, thus rendering the manufacture of the device inexpensive and rapid.

15 The outer diameter of the helicoid spindle 3, in the finished form of the cork puller, is substantially equal to the diameter of the head 4 of this element. Thus when the cork puller and the screw-driver are assembled for carrying, the whole constitutes an article of substantially the same diameter throughout its entire length, with no protuberances to catch in the clothing.

I claim:

25 1. The combination in a bottle opener, of an element comprising a helicoid spindle and a cylindrical head, integrally formed therewith, said head having an annular groove and a transversely extending opening formed therein; and a second element having a shank adapted to be positioned within said helicoid spindle for carrying purposes, or to be positioned within the opening in the head of the first element for co-operating therewith to perform bottle-opening functions.

2. The combination in a bottle opener, of an element comprising a helicoid spindle and a substantially cylindrical head integrally formed therewith and being of a diameter substantially equal to that of the outer diameter of said helicoid spindle, said head having an annular groove and a transversely extending opening formed therein; and a second element having a shank adapted to be positioned within said helicoid spindle for carrying purposes, or to be positioned within the opening in the head of the first element for co-operating therewith to perform bottle-opening functions.

3. The combination in a bottle opener, of an element comprising a helicoid spindle and a cylindrical head integrally formed therewith, said head having an annular

stantially cylindrical opening formed therein; and a second element having a substantially round and tapered shank adapted to be positioned within said helicoid spindle for carrying purposes, or to be positioned within the opening in the head of the first element for co-operating therewith to perform bottle-opening functions.

4. The combination in a bottle opener, of an element comprising a helicoid spindle and a substantially cylindrical head integrally formed therewith and being of a diameter substantially equal to that of the outer diameter of said helicoid spindle, said head having an annular groove and a transversely extending substantially cylindrical opening formed therein; and a second element having a substantially round and tapered shank adapted to be positioned within said helicoid spindle for carrying purposes, or to be positioned within the opening in the head of the first element for co-operating therewith to perform bottle-opening functions, 70 said second element having a cylindrical head of a diameter substantially equal to that of the head of the first said element.

5. The combination in a bottle opener, of an element comprising a helicoid spindle and a cylindrical head integrally formed therewith, said head having an annular groove and a transversely extending opening formed therein; and a second element having a shank provided with a wedge-shaped point and a flared cylindrical head, said shank being adapted to be positioned within said helicoid spindle for carrying purposes, or to be positioned within the opening in the head of the first element for co-operating therewith to perform bottle-opening functions. 85

6. The combination in a bottle opener, of an element comprising a helicoid spindle in the form of a left-hand screw and a cylindrical head integrally formed therewith, said head having an annular groove and a transversely extending opening formed therein; and a second element having a shank adapted to be positioned within said helicoid spindle for carrying purposes, or to be positioned within the opening in the head of the first element for co-operating therewith to perform bottle-opening functions. 95

EDWARD E. LA SCHUM.
